UNITED STATES PATENT OFFICE.

MICHAEL B. RYAN, OF MILFORD, CONNECTICUT.

CHAIN-LINK.

1,260,065.

Specification of Letters Patent. Patented Mar. 19, 1918.

Application filed February 9, 1916. Serial No. 77,113.

To all whom it may concern:

Be it known that I, MICHAEL B. RYAN, of Milford, in the county of New Haven and in the State of Connecticut, have invented 5 a certain new and useful Improvement in Chain-Links, and do hereby declare that the following is a full, clear, and exact description thereof.

The object of my invention has been to 10 provide a welded chain link which shall have, among other advantages, those of being adapted to the making of a comparatively perfect weld; of requiring a minimum amount of wire, and of being free 15 from shoulders or projections that are liable to catch; and to such ends may invention consists in the welded chain link hereinafter specified.

In the accompanying drawings—

20 Figure 1 is a plan view of a blank adapted to form my link;

Fig. 2 is a plan view of a section of chain whose links embody my invention, the links being plain; and,

25 Fig. 3 is a similar view of a section of chain in which the links are twisted.

My invention is capable of embodiment in different forms, and while I shall illustrate it by a description of two embodiments, it is to be understood that such embodiments are only typical of many other embodiments of which it is capable, and my 30 claims are not to be restricted thereto.

Referring to Figs. 1, 2 and 3, the blank 1 35 consists of a length of wire which is severed by diagonal cuts that form beveled faces 2 and 3 upon opposite ends of the blank, one of which slants upward and one of which slants downward, so to speak. This blank 40 is cheap to form since the cut which severs the blank from the rod at the same time makes both the rearmost face on the severed blank and the foremost face on the next blank to be severed. In fact, the blank is 45 practically as cheap to form as if it merely had a squared end.

A link 4 (as shown in Fig. 2) is formed 50 by bending the blank upon itself at each end until its beveled faces 2 and 3 are in contact with each other, and until the ends of the blank rest upon the adjacent strand 5 formed by the central portion of the link. Thus two eyes 6 and 7 are formed, which are, or may be, of equal size.

55 By welding the faces 2 and 3 together,

the extremities of the link are converted into a continuous strand 8, so that the link is, in effect, a closed loop formed of one continuous wire, the strand 8 to be welded to the adjacent strand 5 by welding either 60 one or both of the extremities to the strand 5.

If desired, the links, after being formed as shown in Fig. 2, or at the same time as being so formed, may be twisted as shown 65 in Fig. 3.

My chain link has the following advantages:

It is made with a minimum of wire, the length of the blank being no greater than if it were originally formed in link shape 70 instead of being formed from a section of wire.

The link (when properly welded) is as strong as if it were first formed of a continuous loop.

Because of the freedom of escape of molten metal, both the weld between the beveled faces of the ends of the blank, and that between the ends and the adjacent strand 5 of the link, can be perfectly formed 80 and without blow-holes, bubbles or other weaknesses.

This double welding can be perfectly performed by a single operation.

The beveled ends of the blank not only 85 permit a wire to be formed that is as strong as if the wire were continuous originally, but it results in a joint having the shape and size of the wire itself, and thus without shoulders or projections that might catch 90 and prevent the free running of the chain. This advantage also avoids any necessity for finishing the link to remove such shoulders or projections.

Applicant's link is practically a double 95 link, and is about twice as long as an ordinary open welded link made of the same size of wire, so that it is in effect two links made with a single weld. If the link were made open with the same size of wire, the 100 wire would be likely to become distorted in use. The closing of the wire together, and welding at the middle of the link, braces the link against bends and distortions to a considerable extent.

105 While applicant's link is braced by welding, the welds running lengthwise of the wire cause the strains to be straight in the direction of the length of the wire, instead of twisted or crosswise, and thus the welds 110

are able to stand all of the strain which can be brought upon them, and the welds can be made of sufficient strength so that the wire will break in nearly every instance 5 instead of the weld.

I claim:

1. A chain link comprising a wire loop having a side bent to extend along the longitudinal axis of the loop, the ends of said 10 wire forming the opposite side thereof being similarly bent to lie along the first mentioned side, said sides being welded together at their contacting portions.
2. A chain link comprising a wire loop 15 having a side bent to extend along the longitudinal axis of the loop, the ends of said wire forming the opposite side thereof and being similarly bent to lie along the first mentioned side, said sides being welded together at their contacting portions, and said ends being welded together.
3. A chain link comprising two end eyes connected by contacting parallel side portions, the ends of said link meeting to form 20

one side portion, said side portions being 25 welded together at their points of contact.

4. A chain link comprising two end eyes connected by contacting parallel side portions, the ends of said link meeting to form 30 one side portion, said side portions being welded together at their points of contact, and said ends being welded together.

5. A chain link comprising a wire strand in the shape of a loop having ends abutting and lying along one side of the loop, said 35 ends being welded to the above mentioned side of said loop.

6. A chain link comprising a wire strand in the shape of a loop having ends abutting and lying along one side of the loop, said 40 ends being welded to the above mentioned side of said loop and to each other.

In testimony that I claim the foregoing I have hereunto set my hand.

MICHAEL B. RYAN.

Witnesses:

CHRISTY NELSON,
ANNA GLASS.
